US00D776703S

(12) United States Design Patent (10) Patent No.: US D776,703 S
Shoemaker et al. (45) Date of Patent: * Jan. 17, 2017

(54) DISHWASHER WITH GRAPHICAL USER INTERFACE

(71) Applicant: Sears Brands, L.L.C., Hoffman Estates, IL (US)

(72) Inventors: Anthony Shoemaker, Bartlett, IL (US); Jason Silverstein, Hoffman Estates, IL (US); Trevor Haney, Jenison, MI (US); Joel Fletty, Stevensville, MI (US)

(73) Assignee: SEARS BRANDS, L.L.C., Hoffman Estates, IL (US)

() Term: 15 Years

(21) Appl. No.: 29/528,355

(22) Filed: May 28, 2015

(51) LOC (10) Cl. 14-04
(52) U.S. Cl. USPC D14/487; D14/490; D32/28
